UNITED STATES PATENT OFFICE.

GEORGE W. WEISS, OF BROOKLYN, NEW YORK.

PLAITING ATTACHMENT FOR SEWING-MACHINES.

SPECIFICATION forming part of Letters Patent No. 417,692, dated December 17, 1889.

Application filed November 19, 1888. Serial No. 291,288. (Model.)

To all whom it may concern:

Be it known that I, GEORGE W. WEISS, of Brooklyn, in the county of Kings and State of New York, have invented a new and useful 5 Improvement in Attachments for Sewing-Machines, of which the following is a specification.

My improvement relates more particularly to attachments for plaiting fabric employed 10 in conjunction with a sewing-machine.

I will describe an attachment embodying my improvement in detail, and then point out the novel features in claims.

In the accompanying drawings, Figure 1 is 15 a side elevation showing a portion of a sewing-machine having an attachment embodying my improvement arranged thereon. Fig. 2 is an end view of the same. Fig. 3 is a plan of the same. Fig. 4 is a plan of certain 20 parts; certain other parts being shown in horizontal section. Fig. 5 is a view similar to Fig. 4, but showing a modification of certain parts. Fig. 6 is a detail view in vertical section, showing the mode of forming one 25 kind of plaiting. Figs. 7 and 8 are similar views showing the mode of forming other kinds of plaiting.

Similar letters of reference designate corresponding parts in all the figures.

30 I have only illustrated such parts of a sewing-machine as are essential to a proper understanding of my improvement, as the same does not broadly constitute part of my invention.

35 A designates the bed-plate; B, the head; B', the needle-bar, and B² the presser-foot. These may be of the usual or any desired construction.

40 C designates a frame secured upon the head of the machine, as here shown, by means of screws passing through an arm on the frame, arranged to extend along the front of the head. The frame proper is arranged at the side of the head. It is provided with two 45 downwardly-projecting portions or arms a a'. On the arm a' is a detent-lever D, fulcrumed, as here shown, upon a screw a². The detent-lever comprises a sliding section a⁴, secured in any position into which it may be adjusted 50 by a set-screw a⁵ passing through a longitudinal slot in the sliding section and engaging

the fixed section. Near the outer extremity of the sliding section a⁴ the same is provided with a notch a⁶ upon its under side.

D' designates an L-shaped slider bar or 55 rod, which slider-bar constitutes a support for a folder D² for material to be plaited. An arm b of the slider-bar passes loosely through suitably-formed apertures in the arms a a' of the frame C, and is adapted to be slid to 60 and fro therein. The other arm b' of the bar or rod extends downwardly to near the bed A. It is shown as extending at a slightly-inward incline.

The folder D² is secured in the lower end 65 of the arm b', as shown, by means of a screw b² passing through the arm, and an upturned portion b³ on the folder, which enters a slot b⁴ in the arm. The folder D² extends approximately parallel with and close to the bed A. 70

E designates a plate mounted upon the bed A and longitudinally adjustable thereon. A set-screw e, passing through a slot e' and engaging a tapped hole in the bed-plate, operates to secure the plate E in any position into 75 which it may be adjusted. The plate E has its forward end portion, or that portion which is nearer the needle, elevated somewhat above the bed A, and is arranged in such position relatively to the folder D² that when the 80 slider-bar D' is moved inwardly the folder D² will pass freely beneath said raised end portion of the plate E. If a piece of cloth be placed beneath the folder and above the plate E and the folder be moved inwardly, the 85 cloth will be carried with the folder beneath the plate, so as to form a plait or fold, as shown in either of the Figs. 6, 7, or 8. When the folder has thus been moved inwardly to form a fold or plait in the cloth, it is retained 90 in such position by means of the detent D, the notch a⁶ of which engages a projection a⁸ on the arm b of the slider bar or rod D'. In the example of my improvement shown such projection consists of a screw operating as a 95 set-screw to retain a downwardly-extending arm a⁹ upon the slider bar or rod. A coil-spring a¹⁰ tends to maintain the detent in engagement with the slider-rod. The detent may be rocked by hand to release the slider-rod. When so rocked, a spring a'', extending 100 between the arm a⁹ and the portion a of the

frame, causes the slider-rod to move outwardly and the folder D² to be consequently moved from beneath the plate E.

F designates a spacer, by which the spaces between the plaits are regulated. In the example of my improvement shown in Figs. 1, 2, 3, and 4, the spacer comprises an approximately straight bar, a portion of which extends over the plate E. That portion which extends over the plate E is knife-edged upon each side. It is also provided with a projection or pointer extending into proximity with a scale upon the plate E and over a longitudinally-extending slot e² in the plate E.

15 E² designates a support for the spacer. This support is approximately U-shaped. One of its arms f passes through suitable apertures in the arms a a' of the frame C, in which it is rigidly secured, and the other f' has mounted 20 upon it the spacer F. It will be seen more clearly, by reference to Fig. 2, that the support E² extends downwardly and outwardly at an angle, although this I do not deem essential.

25 The spacer F not only operates to regulate the spaces between the plaits, but it also operates as a presser to retain the cloth being worked against the plate E, so that it may be satisfactorily operated upon by the needle.

30 This latter function is performed through the agency of a spring g, which spring is secured near one end upon a collar g', surrounding the arm f' of the support E², and constitutes, in effect, a part of the spacer. The collar g' 35 may be slid along upon the arm f', and may, together with the spacer, also be rotated upon the arm f'. When rotated in one direction, the spring g will be caused to bear upon the spacer F and to exert pressure upon the latter 40 to hold it firmly upon the cloth. A set-screw g² operates to retain the collar g' in any position into which it may be adjusted. The presser F at its rear end, or that end which is supported upon the arm f', is bifurcated, the bifurcated portions being provided with suitable apertures, through which the arm f' extends. The arm f' extends loosely through these apertures, so that the presser may be moved along on the arm. The collar g' is arranged 45 between the bifurcated portions of the presser. When, therefore, the set-screw g² is set, the presser is prevented from being moved along on the arm f'.

50 My improved attachment has numerous functions. It not only provides for regulating the spaces between the plaits and the width of the plaits, but numerous different kinds of plaits can be produced with it. The spaces between the plaits are regulated by 55 moving the spacer F along upon the arm f', either nearer to or farther from the needle. The width of the plaits is regulated by moving the section a⁴ of the detent D longitudinally on the fixed portion, whereby a greater or lesser length of movement of the slider-bar D' will be required in order to cause the de-

tent to engage it, and consequently whereby the folder D² will be moved for a greater or less distance beneath the plate E.

In Fig. 6 I have illustrated an ordinary form 70 of plaiting of fold-over folds.

In Fig. 7 I have illustrated a form of plaiting in which the two folds extend toward each other, and in Fig. 8 I have shown a form of plaiting in which the folds extend away from 75 each other, but which are formed upon the face of the goods. This last form of plaiting is made by a spacer of modified form. (Shown more clearly in Fig. 5.) The spacer is of such form that it extends to the outside of the plate 80 E and below the same, as shown in Fig. 8.

By the use of my improvement the necessity for folding the cloth is avoided, while there is no necessity for keeping it stretched, as the spacer always bears against the seam 85 of the plait previously sewed and the folder maintains a sufficient tension on the goods. The attachment may be applied to any sewing-machine having a rigid head.

What I claim as my invention, and desire 90 to secure by Letters Patent, is—

1. The combination, with a head of a sewing-machine, of a frame mounted on said head, an adjustable detent mounted on said frame, a fixed pivot upon which said detent 95 may slide, a spring-actuated slider-rod sliding in said frame and having a portion extending downwardly to near the bed of the machine, a spring acting on said detent to cause it to engage said slider-rod when the latter is moved in one direction, a folder mounted on said slider-rod, and an adjustable plate mounted upon the bed of the machine and beneath which the folder may be moved by the slider-rod, substantially as specified. 100

2. The combination, with a frame, of an adjustable detent mounted on said frame, a spring-actuated slider-rod sliding in said frame, a spring acting on the detent to cause 110 it to engage the slider-rod when the latter is moved in one direction, a folder mounted on said slider-rod, an adjustable plate beneath which the folder may be moved by the slider-rod, a combined spacer and presser, and a 115 rigid support for said spacer and presser, upon which said spacer and presser are adjustably secured, substantially as specified.

3. The combination, with a slider-rod, of a detent, a spring acting on said detent to cause 120 it to engage the slider-rod when the latter is moved in one direction, a folder on said slider-rod, an adjustable plate beneath which the folder may be moved by the slider-rod, a spacer, and a support for the spacer, said 125 spacer comprising a bar and a collar g', provided with a spring g, substantially as and for the purpose specified.

GEORGE W. WEISS.
